UNITED STATES PATENT OFFICE.

JACOB GRUENEBAUM, OF NEW YORK, N. Y., ASSIGNOR OF ONE-HALF TO
CHARLES A. HESS, OF SAME PLACE.

FLASK OR BOTTLE.

SPECIFICATION forming part of Letters Patent No. 284,127, dated August 28, 1883.

Application filed April 28, 1883. (No model.)

To all whom it may concern:

Be it known that I, JACOB GRUENEBAUM, a subject of the Emperor of Germany, residing in the city of New York, in the county and 5 State of New York, have invented a new and useful Improvement in Flasks or Bottles; and I do hereby declare that the following is a full, clear, and exact description of the invention, which will enable others skilled in the art to 10 which it appertains to make and use the same.

My invention relates to improvements in flasks, bottles, and jugs, and other like vessels for holding wines, liquors, perfumeries, and other fluids; and the object of my improvement is a flask or other vessel so constructed 15 as to hold separate at the same time two or more different kinds of fluids, and provided with a separate neck and mouth for each different kind of fluid. I attain this object by 20 separating the flask, bottle, or other vessel into two or more compartments or chambers by means of a partition or partitions, and giving to each compartment or chamber a separate neck and mouth.

25 The annexed drawings will further illustrate the improvement. The drawings show a flask with but two chambers; but more may be added, if desired.

Figure 1 represents a front elevation. Fig. 2 represents a longitudinal vertical section at $x x$ in Fig. 1. Fig. 3 represents a top view. Fig. 4 represents a horizontal section taken at $y y$ in Fig. 1.

The flask, bottle, or other vessel with this improvement may be made of glass, earthenware, china, or other desired material, and may be of any desired size, pattern, or form. By means

of the partition or partitions above referred to, it is divided into two or more chambers of equal or unequal size, as desired. Each chamber is provided with a separate neck and mouth furnished with any approved stopple. The neck to each chamber is inclined from the perpendicular at any desired angle, and the necks of two contiguous chambers are inclined in opposite directions. The useful purposes of such inclination are, among others, to facilitate drinking and pouring any liquid from the flask. The inclination of the neck through which the liquid is to be poured obviates the raising of 50 the flask as high as when the neck is straight, and renders drinking therefrom more convenient, while the inclination of the other neck in the opposite direction obviates contact between it and the face. A further useful purpose of 55 such inclination is that a place is provided at $c c$, Fig. 1, for fastening a strap or cord to the flask, by which it may be suspended from the person or from a belt. This is especially useful when the flask is used for the purposes of 60 a canteen, or on a fishing or hunting excursion.

What I claim as my invention, and desire to secure by Letters Patent, is—

A flask or bottle having two or more separate chambers, each chamber provided with a 65 separate neck at the same end of the bottle, said necks being inclined in different directions, substantially as described, as and for the purposes as described.

JACOB GRUENEBAUM.

In presence of—

W. J. TOWNSEND,
ALBERTUS PERRY.
